UNITED STATES PATENT OFFICE

FRED ASHWORTH, OF BEVERLY, MASSACHUSETTS, ASSIGNOR TO UNITED SHOE MACHINE CORPORATION, OF PATERSON, NEW JERSEY, A CORPORATION OF NEW JERSEY

SEWING MACHINE SHUTTLE

Original application filed September 24, 1929, Serial No. 394,770. Divided and this application filed May 1, 1930. Serial No. 448,910.

The present invention relates to sewing machine shuttles, and has for its object the provision of a discoidal shuttle and thread holder case having a simple and improved construction and arrangement of its various parts.

The present invention is intended primarily as an improvement on the shuttle and thread holder case disclosed in applicant's prior application Serial No. 338,756, filed February 9, 1929, and is herein illustrated as embodied in a shuttle casing and thread holder similar in many respects to those disclosed in the application above referred to.

15 The shuttle casing and thread holder of the present invention, however, are arranged to allow the thread to be drawn from the outside of the thread mass or thread cop instead of from the inside, and embody certain novel 20 features of construction particularly designed for use in connection with a thread holder in which the thread is drawn from the outside of the thread mass. Except as defined in the claims, however, the several 25 features of the invention are not limited to use in a construction in which the thread is led from the outside instead of from the inside of the cop.

The several features of the present invention together with the advantages to be obtained thereby will be readily understood by those skilled in the art from the following description taken in connection with the accompanying drawings in which Fig. 1 is a 30 detail front view of the improved shuttle and thread holder; Fig. 2 is a detail sectional view of the shuttle and thread holder, taken on the line 2-2 of Fig. 1; Fig. 3 is a detail sectional view of the thread holder removed 35 from the shuttle and with the locking arm in raised position to permit threading of the thread holder.

The present application is a division of applicant's pending application Serial No. 45 394,770, filed September 24, 1929, the shuttle and thread holder being identical in construction with those disclosed in said application.

As illustrated in the drawings the discoidal 50 shuttle casing is indicated at 4. The rear end

of this casing is closed and the forward end is open to receive the thread holder. The thread holder indicated at 6 consists of a cylindrical thread case, the rear end of which is open to permit the insertion of a cop of thread while the holder is removed from the shuttle, and the front end of which, when the thread case is in position in the shuttle, forms a closure for the open end of the shuttle casing, the construction as so far described 55 being substantially the same as that disclosed in applicant's prior application. From the closed end of the thread case 6 a stud 8 extends inwardly to form a central support for the thread mass or cop and within this stud a 60 spring pressed plunger 10 is mounted. This plunger, however, instead of being pressed inwardly as in applicant's prior construction, is pressed outwardly and its outward movement is limited by a washer 12 seated in 65 under-cut grooves formed in the outer end of the thread case and forming a guideway for the locking slide hereinafter described. When the thread holder casing, properly threaded, is in position in the shuttle casing, 70 as indicated in Figs. 1 and 2, the thread leads from the outside of the thread mass through an opening in the side wall of the thread holder case and then radially inward over the outer end of the thread holder case to a 75 central opening 14 formed in an overlying arm 16. The opening 14 is directly over the outer end of the plunger 10, and the thread in its passage from the thread mass to the opening passes between the inner surface of 80 the arm 16, and the outer end of the plunger. The shuttle thread is thus subjected to sufficient pressure to produce the required tension on the thread.

85 Means for locking the thread case securely in position in the shuttle casing, while permitting its ready removal, comprise a flange 18 projecting radially from the inner end of the thread case and adapted to engage a slot formed in the wall of the shuttle casing, and the arm 16, the free end of which is arranged to engage a groove 20 formed in the shuttle casing diametrically opposite the slot which receives the flange 18. To permit 90 the arm 16 to be moved into and out of en- 95

gagement with the groove 20, it is mounted upon a slide 22 which is arranged to move in a diametrically arranged guideway formed by the undercut grooves 24 in the outer end 5 of the thread case 6. The thread case can be readily removed from the shuttle casing by moving the slide 22 towards the right, as viewed in Figs. 1 and 2, until the end of the arm 16 moves out of engagement with the groove 20 and by then tilting the thread case slightly so as to disengage the flange 18 from its cooperating slot. The thread case can be completely threaded before it is replaced in the shuttle casing. In order to 10 facilitate the threading operation, the arm 16 is pivotally mounted upon the slide 22 at 26. This permits the arm 16 to be swung outwardly into the position indicated in Fig. 3, in which position the end of the shuttle 15 thread can readily be passed outwardly through the opening 14. When the locking slide 22 and arm 16 are moved to the left, as viewed in Figs. 1 and 2, to lock the thread case in the shuttle casing, the arm 16 is held 20 down against the plunger 10 by the engagement of the outer end of the arm 16 with the shuttle casing. To assist in this action, and also to guide the arm 16 accurately into engagement with the groove 20, projecting 25 lugs 28 are formed at the sides of the arm 16 near its outer end and are arranged to engage the slots 24 which are extended completely across the outer end of the thread case for this purpose. Openings 30 formed 30 in the outer end of the thread case permit an outward movement of the arm 16 to the position indicated in Fig. 3, after the arm together with the slide 22 has been moved diametrically of the thread case a sufficient 35 distance to disengage the arm from the groove 20. The withdrawing movement of the slide 22 is limited by a stop pin 32 projecting from the outer end of the thread case. The slide 22 with the arm 16 is held in locking 40 position by the engagement of the outer end of the plunger 10 with a correspondingly shaped recess formed in the under side of the arm 16. The plunger is disengaged from its recess when it is desired to remove the thread 45 holder case from the shuttle casing by inserting a suitably shaped tool through the opening 14 and forcing the plunger inwardly. The invention having been described, what 50 is claimed is:

55 1. A sewing machine shuttle comprising a discoidal shuttle casing having an open end, a removable thread holder forming a closure for the open end of the shuttle casing, provided with a stud projecting inwardly into the shuttle casing and forming a central support for the shuttle thread mass, a thread engaging plunger mounted in said stud, means for removably locking the thread holder to the shuttle casing, comprising a locking slide mounted in the end of the

60

65

thread holder casing to move diametrically into engagement with the shuttle casing, and a spring arranged to press said plunger outwardly towards a surface formed on the slide between which surface and the plunger the thread passes on its way from the shuttle to the work. 70

2. A sewing machine shuttle comprising a discoidal shuttle casing having an open end and a removable thread holder forming a closure for the open end of the shuttle casing, provided with a stud projecting inwardly into the shuttle casing and forming a central support for the shuttle thread mass, means for removably locking the thread holder to the shuttle casing, comprising a locking slide mounted in the end of the thread holder casing to move diametrically into engagement with the shuttle casing, a plunger mounted in said stud arranged to engage a hole in the slide when the slide is in locking position, and a spring arranged to press said plunger outwardly into engagement with said hole and towards a surface on the slide between which and the plunger the thread passes on its way from the shuttle to the work. 80

3. A sewing machine shuttle comprising a discoidal shuttle casing having an open end and a removable thread holder forming a closure for the open end of the shuttle casing, provided with a stud projecting inwardly into the shuttle casing and forming a central support for the shuttle thread mass, means for removably locking the thread holder to the shuttle casing, comprising a locking slide mounted in the end of the thread holder casing to move diametrically into engagement with the shuttle casing, an arm pivotally mounted on said slide provided with a hole through which the thread passes on its way from the shuttle to the work, a thread engaging plunger mounted in said stud, and a spring arranged to press said plunger outwardly into engagement with the thread in its passage to the hole in said arm. 95

4. A sewing machine shuttle comprising a discoidal shuttle casing having an open end, a removable thread holder forming a closure for the open end of the shuttle casing, provided with a stud projecting inwardly into the shuttle casing and forming a central support for the shuttle thread mass, an arm pivotally mounted on the end of the thread holder casing, provided with a hole through which the thread passes on its way from the shuttle to the work, a thread engaging plunger mounted in said stud, and a spring arranged to press said plunger outwardly into engagement with the thread in its passage to the hole in said arm. 110

5. A sewing machine shuttle comprising a discoidal shuttle casing having an open end, a removable thread holder forming a closure for the open end of the shuttle casing, pro-

vided with a stud projecting inwardly into the shuttle casing and forming a central support for the shuttle thread mass, a thread engaging plunger mounted in said stud, means for removably locking the thread holder to the shuttle casing, and a spring arranged to press said plunger outwardly towards a surface at the outer end of the thread holder casing between which surface and the plunger the thread passes on its way from the shuttle to the work.

6. A sewing machine shuttle comprising a discoidal shuttle casing having an open end and a removable thread holder forming a closure for the open end of the shuttle casing provided with a stud projecting inwardly into the shuttle casing and forming a central support for the shuttle thread mass, means for removably locking the thread holder to the shuttle casing, comprising a locking slide mounted in the end of the thread holder casing to move diametrically into engagement with the shuttle casing, and an arm pivotally mounted on said slide provided with a hole through which the thread passes on its way from the shuttle to the work.

In testimony whereof I have signed my name to this specification.

FRED ASHWORTH.
